FREDERICK E. HARPST, OF HOUSTON, TEXAS, ASSIGNOR OF TWENTY-FIVE ONE-HUNDREDTHS TO W. O. ILFREY, OF HOUSTON, TEXAS.

ROTARY-VALVE MECHANISM.

1,141,958.

Specification of Letters Patent. Patented June 8, 1915.

Application filed May 18, 1914. Serial No. 839,292.

To all whom it may concern:

Be it known that I, FREDERICK E. HARPST, a citizen of the United States, residing at Houston, in the county of Harris and State 5 of Texas, have invented certain new and useful Improvements in Rotary-Valve Mechanism, of which the following is a specification.

This invention relates to new and useful 10 improvements in rotary valve mechanism.

The object of the invention is to provide 15 a valve of the character described, adapted to be used in connection with the cylinder of an internal combustion engine, for the purpose of regulating the intake of the charge, and the exhaust after the explosion of said charge.

Another object of the invention resides in 20 the provision of a hollow rotary valve having intake or exhaust ports adapted to register with corresponding intake or exhaust ports of the cylinder, said valve being operatively connected with a mechanism which imparts an oscillating movement thereto as 25 the valve rotates, said intake or exhaust ports being formed at such an angle relative to the axis of valve rotation as to prolong the full opening of said ports.

A still further feature of the invention re- 30 sides in the provision of a pressure plate, which partially surrounds the valve and holds the same against its seat, said plate being held resiliently against the valve, by means of a pneumatic cushion.

35 A still further feature of the invention resides in the provision of means whereby the pneumatic pressure against said plate may be readily controlled.

With the above and other objects in view, 40 as will be more specifically pointed out hereinafter, the invention has particular relation to certain novel features of construction, operation and arrangement of parts, an example of which is given in this specification 45 and illustrated in the accompanying drawings, wherein,

Figure 1 is a longitudinal vertical section through a cylinder head, showing a valve chamber and a rotary valve therein, and Fig. 50 2 is a transverse vertical sectional view thereof.

Referring now more particularly to the drawings, wherein like numerals of reference designate similar parts in each of the

figures, the numerals 1 and 2 refer, respectively, to two cylinders of an engine, having the cylinder head 3. This head has the parallel lengthwise extending valve chambers 4 and 5. The bottom of these chambers are formed into seats 6 and 7, arcuate in cross section, whereon rotates the hollow cylindrical valves 8 and 9. Each valve is held against its seat by means of the pressure plate 10, formed of hollow casting and which extends from end to end and side to side of its valve chamber and which has a limited vertical movement therein, as hereinafter explained. The under side of the pressure plate is arcuate in cross section, forming a seat 11 which rests upon the corresponding valve. Each valve is provided with two oppositely disposed ports, as 12, near one end and two oppositely disposed ports, as 13, near the other end, said ports being formed at an angle to the axis of rotation and the ports 12 being inclined in the reverse direction of that of the ports 13, and being staggered relative thereto, as indicated in Fig. 1.

The valve 8, as shown, has exhaust ports 80 and the valve 9 is provided with intake ports, as 14, corresponding in number and arrangement with the exhaust ports of the valve 8. Each cylinder is arranged to communicate with one set of exhaust and one 85 set of intake ports of the valves 8 and 9, through the ports 16 and 17 in the cylinder head 5. These last mentioned ports are also arranged at an angle corresponding to the valve ports, with which they register so as 90 to provide for a perfect registration of the ports as the valves rotate. The seats 6 and 7, as well as the seats 11, are provided with lengthwise extending grooves, which extend some distance on each side of the valve ports, 59 but not far enough to connect said ports, and the valves 8 and 9 may also be similarly grooved, if desired. These grooves serve to facilitate lubrication, in that they hold the lubricant and the grooves in the seats also 100 present a more perfect bearing surface for the valve, inasmuch as particles of carbon or other foreign matter will find their way into said grooves and said foreign matter will thus not be retained between the valve 105 and seat.

A cap 18 is secured on the cylinder head 3 and incloses the chambers 4 and 5 and be-

tween this cap and the cylinder head is a metallic washer 19. Secured between this cap and washer are flexible diaphragms 20, 20, preferably formed of metal which may 5 be corrugated, if desired, to make more elastic, and the portions of the cap 18, opposite the chambers 4 and 5 are hollowed out, so as to leave spaces 15, 15, between the respective diaphragms and cap opposite the 10 respective cylinders 4 and 5. The partition 21, separating the chambers 4 and 5 has a fluid passageway 22, communicating at one end with the interior of the cylinder and at its other end dividing and communicating 15 with each of the spaces 15, 15 above the diaphragms 21, 21 and compression is thus admitted through the passageway 22 and passageways 23, into the spaces 15, 15. The diaphragms 20, 20 have studs 24 secured thereto 20 which depend therefrom and rest against the pressure plate underneath. As is obvious from an inspection of Fig. 1, each pressure plate will be held against its valve by its corresponding stud 24. It is obvious 25 that the pressure above the diaphragms 20, 20 may be regulated, as desired, so that as the pressure in the cylinder increases, the downward pressure on the pressure plates will increase to a corresponding degree, so 30 that the valve will be held firmly against its seat at the times of greatest pressure and at other times the pressure of the valve against its seat will be lighter, thus obviating any unnecessary wear on the valve. Interposed between the lower end of each stud 35 24 and its corresponding pressure plate is a flat arcuate spring or other resilient member 24', which is of sufficient strength to normally hold the valve seated but should any large foreign body become interposed between the valve and seat will permit the valve to rise and thus avoid injury thereto and permit the foreign body to pass from the valve seat.

40 The pressure plate has ports, such as 25, to register with the ports in the valves and which lead out, as shown in Fig. 2, and communicate with the ports such as 26 in the walls of the valve chamber. Each pressure plate is cast hollow and is provided with one or more nipples such as 22 which is passed through the end of the cylinder head and threaded into the end of the pressure plate and through this nipple water may be 45 introduced, and circulated into the interior of the pressure plate, so as to keep the same and the valve cool. The orifice in the end plate through which the nipple passes is oblong vertically, so as to permit said nipple to have a certain amount of vertical play as the pressure plate moves up and down. Adjusting screws, as 30, are threaded through the cap 18, and their lower ends contact 50 against the upper ends of said studs 24 and by means of these screws the play of the

studs 24 and the corresponding diaphragm may be limited and the vibration of the diaphragm reduced to a minimum during the suction stroke and fluctuations in pressure in the cylinder. Suitable bearings 31 and 32 are provided which are carried by bearing plates, one secured to each end of the cylinder head. One end of each valve is attached to a shaft 33, which extends through the bearing 32 and a worm gear wheel 34 70 is slidably mounted upon, but keyed to the outer end of said shaft and said gear wheel is inclosed by a suitable casing 35. Rotation is imparted to the valve through this gear wheel by any suitable mechanism, not shown, in operative connection with the engine. A cylindrical block 36 rotates in the bearing 31 and a plunger 37 passes axially through this block and is threaded into the adjacent end of the valve and the block is 80 keyed to the valve so that they rotate together.

The bearings 31 and 32 are enlarged vertically, or oblong, so as to allow a certain amount of vertical play to the shaft 33 and 90 block 36 to permit the rising of the valve from its seat as hereinbefore explained.

The bearing 31 is provided with a plug 39, which carries an inwardly extending stud 40, whose inner end has a roller 41, which 95 operates in the groove 42 in the periphery of the block 36. This groove is cam-shaped and as the valve rotates causes an endwise motion thereof and the shape of the groove is such that when the valve ports begin to 100 open or close, a sudden endwise thrust is imparted to the valve, which in combination with the rotary movement of the valve causes a quick opening and closing, but when the ports register, the groove is so 105 shaped that there will be very little or no endwise motion to the valve, thus prolonging a full port opening and providing freer exhaust and intake. The passageway 22 is provided with a valve 43, by means of which 110 said passageway may be controlled and the pressure above the diaphragms regulated.

In Fig. 2 there is illustrated an oil duct 44 through which a lubricant may be admitted to the valve seat.

115 It should further be noted that the inclination of the ports causes the edges of the registering ports to meet with a shearing effect and the particles of carbon which, at the moment of closing, engage between said 120 edges, will be easier cut away, thus preventing the wearing of said edges.

What I claim is:

1. In a device of the character described, the combination with an internal combustion 125 engine cylinder, of a head secured to said cylinder, said head having a cylindrical chamber extending transversely relative to the engine cylinder, a hollow rotary valve in said chamber, opposing ports in the valve 130

wall, said ports having a corresponding inclination to the axis of rotation, a corresponding port communicating with the interior of the cylinder and arranged to register with the valve port as the valve rotates, said cylinder ports having a corresponding inclination to the valve ports, means for rotating the valve and means for imparting a lengthwise movement to the valve while said ports are registering.

2. In a device of the character described, a valve chamber, a hollow rotary valve therein, provided with ports inclined to the axis of rotation, an internal combustion engine cylinder to which the valve chamber is secured, inlets thereto arranged to register with the valve ports and having a corresponding inclination, a seat in the chamber wherein said valve rotates, and means for 20 rotating the valve.

3. In a device of the character described, the combination with an internal combustion engine cylinder, of a head for said cylinder, said head having a cylindrical valve chamber arranged adjacent the cylinder, a port through which said cylinder and chamber communicate, a hollow rotary valve in said chamber being provided with opposing ports, said valve ports and cylinder port being arranged to register and having a corresponding inclination to the axis of valve rotation, a means for rotating the valve and a mechanism in operative connection with the valve and imparting a lengthwise thrust thereto at the time of the registration of a valve port and the cylinder port.

4. In a device of the character described, a valve seat, a rotary valve seated thereon and provided with ports inclined to the axis of rotation, said seat being also provided with ports, which register with the valve ports and have a corresponding inclination to that of said valve ports.

5. In a device of the character described, a valve seat, a rotary valve seated thereon and provided with ports inclined to the axis of rotation, said seat being also provided with ports, which register with the valve ports and have a corresponding inclination to that of said valve ports, means for rotating the valve and a mechanism in operative connection with the valve and impart-

ing a lengthwise thrust thereto during the registration of said ports.

6. In a device of the character described, a valve chamber, a rotary valve therein, a seat in the chamber wherein said valve rotates, a pressure plate operating against the valve and holding said valve against its seat, a diaphragm operating against said pressure plate and means for varying the pneumatic pressure on opposite sides of said diaphragm.

7. In a device of the character described, a valve chamber, a rotary valve therein, a seat whereon said valve rotates, a diaphragm spanning said chamber, a means for introducing pneumatic pressure on the side of said diaphragm opposite the valve whereby said diaphragm is held in resistance against 70 said valve.

8. In a device of the character described, a valve chamber, a rotary valve therein, a seat in the chamber wherein said valve rotates, a diaphragm operating in resistance 75 against the valve and holding the same yieldingly against the seat.

9. In a device of the character described, a valve chamber, a rotary valve therein, a seat in the chamber wherein said valve rotates, a diaphragm operating in resistance 80 against the valve and holding the same yieldingly against the seat, and means for limiting the vibration of said diaphragm.

10. In a device of the character described, a valve seat, a rotary valve seated thereon and provided with ports inclined to the axis of rotation, said seat being also provided with ports which register with the valve ports and have a corresponding inclination to that 90 of said valve ports, means for rotating the valve and a mechanism in operative connection with the valve and imparting a lengthwise thrust thereto at the beginning of the opening and closing of the valve 95 ports.

In testimony whereof I have signed my name to this specification in the presence of two subscribing witnesses.
